(57) CLAIM

I claim the ornamental design for a detachable phone case, as shown and described.

DESCRIPTION

FIG. 1 is a top-rear isometric view of a detachable phone case showing my design;

FIG. 2 is top-front isometric view thereof;

FIG. 3 is a front plan view thereof;

FIG. 4 is a rear plan view thereof;

FIG. 5 is a left side view thereof;

FIG. 6 is a right side view thereof;

FIG. 7 is a top plan view thereof; and,

FIG. 8 is a bottom plan view thereof.

The broken lines depicting a mobile phone illustrates environmental structure that forms no part of the claimed design. All other broken lines shown in the drawings depict portions of the detachable phone case that form no part of the claimed design.
